(57) **CLAIM**

The ornamental design for a three-pack container carrier with tear tab release, as shown and described.

DESCRIPTION

FIG. 1 is a top perspective view of an ornamental design for a three-pack container carrier with tear tab release showing my new design.

FIG. 2 is a bottom perspective view of the three-pack container carrier with tear tab release of FIG. 1.

FIG. 3 is a top view of the three-pack container carrier with tear tab release of FIG. 1.

FIG. 4 is a bottom view of the three-pack container carrier with tear tab release of FIG. 1.

FIG. 5 is a front view of the three-pack container carrier with tear tab release of FIG. 1.

FIG. 6 is a rear view of the three-pack container carrier with tear tab release of FIG. 1.

FIG. 7 is a right side view of the three-pack container carrier with tear tab release of FIG. 1; and,

FIG. 8 is a left side view of the three-pack container carrier with tear tab release of FIG. 1.

1 Claim, 4 Drawing Sheets
